KEY AND PERMUTATION OPERATED
PADLOCKDillwyn M. Bell, River Forest, Ill., assignor to
Dudley Lock Corporation, Chicago, Ill., a cor-
poration of Illinois

Application December 5, 1933, Serial No. 701,022

15 Claims. (Cl. 70—25)

This invention relates to padlocks in which the control of the locking element or shackle is alternatively effected by a permutation mechanism and a key-operated mechanism so that the lock may be opened either by means of a key or by setting up the permutation elements in accordance with a key "combination". The invention includes various improvements in details of construction and in respect to the operation of the elements as herein shown, described and explained, and as indicated by the claims.

In the drawings:

Figure 1 is a face view of a padlock embodying this invention.

Figure 2 is a vertical section on an enlarged scale showing certain portions of the interior mechanism having to do with the operation of the lock by means of a key, the permutation elements being removed from the casing to permit a clearer view of the key-operated parts.

Figure 3 is a similar vertical section taken, however, at a plane farther forward than Figure 2 so as to include portions of the permutation mechanism.

Figure 4 is a horizontal section taken substantially as indicated at line 4—4 on Figure 3.

Figure 5 is a vertical section showing the same parts as Figure 3 but with the shackle shifted through the initial portion of its opening movement.

Figure 6 is a vertical section showing the same parts as Figure 5 but with the shackle shifted farther toward its open position.

Figure 7 is a transverse vertical section taken substantially as indicated at line 7—7 on Figure 5.

For the sake of convenience and clearness the features of construction concerned with the key operation of the lock will be first described. Figure 1 is an external view showing the casing, 1, in which the shackle, 2, is slidably mounted, and which carries on its front face a rotatable dial member, 3, with which there is rigidly associated a knob, 4, for adjusting the dial with respect to a fixed index mark, 5, on the face of the casing, 1. The knob, 4, is formed with a central aperture affording access to the key slot, 6, of the centrally disposed spindle, 7, of the plug or barrel of the key lock. Said spindle, 6, is seen upstanding above the plane of section in Figure 2, while a portion of the barrel, 8, is shown in section journaled in the fixed cylinder, 9, of the key lock which is formed with grooves, 10, into which the

tumblers, 11, of the key lock project for normally holding the plug, 8, against rotation.

A disk or plate, 12, is rigidly associated with the spindle, 7, for rotation therewith, and is formed with a notch, 13, into which there extends the arm of a lever 14, fulcrumed at 15 in the casing. The shackle, 2, has notches, 16, formed in both its legs, and is held in locked position in the casing by a pair of locking dogs, 17, which respectively engage said notches, 16. As seen in Figure 4, these dogs, 17, are similar in shape and are urged yieldingly apart by springs, 18. They are guided for movement into and out of the notches, 16, by the pocket or guide-way, 19, formed in the casing, 1, and are connected for simultaneous movement in opposite directions by means of a lever, 20, which is fulcrumed on a pivot, 21, secured in the upper wall, 1^a, of the casing. The opposite ends of the lever, 20, are notched, as indicated at 22, and said notches engage circular lugs or pivots, 23, projecting from the faces of the dogs, 17, adjacent the lever, 20. Each of the dogs has a lug, 25, projecting from its opposite face, and the lever, 14, has an arm, 24, which normally contacts with one of the lugs, 25, for withdrawing the dogs, 17, from the notches, 16, when the notched plate, 12, is rotated by means of a key inserted in the slot, 6. Preferably, the inner faces of the dogs, 17, are slightly inclined as seen at 17^a, and the cooperating faces of the notches, 16, are similarly inclined at 16^a so that when the shackle is locked any outward pull upon it will tend to crowd the dogs farther toward locking position rather than to force them back out of the notches, 16.

The permutation mechanism includes three notched tumbler disks, 26, 27 and 28, journaled for rotation on the upstanding spindle, 7. A pawl, 29, is fulcrumed on the same pivot, 15, 40 which carries the lever, 14, and is formed with a tooth, 30, dimensioned to enter the notches, 26^a, 27^a and 28^a, of the three tumbler disks when said tumblers are adjusted with the notches in registration with each other and with the tooth, 30, 45 of the pawl. However, to permit entry of the pawl tooth, 30, into the notches, it is necessary that an additional disk or plate, 31, be shifted around the axis of the spindle, 7, to bring its notch, 31^a, into registration with the others. This is effected by a short initial movement of the shackle, 2, toward unlocking position, which is 50 permitted by the excess width of the notches, 16, over the thickness of the locking dogs, 17. At any time while the dogs, 17, remain in locking 55

position, the shackle, 2, may be withdrawn to this extent, as shown in Figure 5; and since the disk or plate, 31, has an arm, 32, engaged with the longer leg, 2^a, of the shackle, 2, (by extension of a terminal lug, 32^a, into a groove, 2^b, of said shackle leg) the initial outward movement of the shackle causes sufficient rotation of the plate, 31, to bring the notch, 31^a, into alignment or registration with the notches of the tumbler disks, and thus permit entry of the pawl tooth, 30, into said notches. The pawl is urged into the notches by means of a relatively heavy spring, 33, coiled about the hub of the coil, and with one end hooked over the tooth portion, 30, while the opposite end reacts against a partition wall of the case. The pawl, 29, includes an arm, 34, which engages the lug, 25, of one of the dogs, 17, so that as the tooth, 30, moves into the registered notches of the permutation tumbler disks, this arm, 34, shifts the dog, 17, out of engagement with the notch, 16, of the shackle, and, simultaneously, the other locking dog, 17, is similarly withdrawn from the other notch of the shackle by virtue of the inter-connection of said dogs through the lever, 20.

With the dogs, 17, thus withdrawn, the shackle, 2, is free to be moved outwardly to open position, and such movement causes further rotation of the plate, 31, through the connection of its arm 30 with the shackle leg, 2^a. The notch of the plate, 31, is formed with one side inclined to a radius of the plate so that this inclined side of the notch shall act cam-wise upon the pawl tooth, 30, forcing it outwardly as the plate is rotated. A second arm, 35, extending from the plate, 31, supports a pivoted ratchet, 36, whose spring, 37, urges it toward the peripheries of the permutation tumbler disks. Each of said disks has a small notch, 38, which is engaged by the ratchet, 36, during the outward movement of the shackle leg, 2^a, so that the permutation disks are thus shifted to carry their deeper notches out of registration with the pawl tooth, 30, as soon as said tooth has been swung clear of said notches by the camming action of the notch, 31^a, just described. The notches of the permutation disks are of approximately the same shape as the notch, 31^a, in the plate, and tend to move in registration with the latter during the withdrawal of the pawl tooth, 30. Thus, by the time the shackle, 2, has arrived at open position, the registered adjustment of the notches of the permutation disks has been destroyed, rendering it impossible for anyone tampering with the lock 55 to discover the combination by any external manipulation of the shackle or the knob, 4. The dogs, 17, are no longer held out of locking position by the lever arm, 34, but their return is blocked by the position of the shackle leg, 2^a, as seen in Figure 6.

While the shackle is open, it may be rotated about the axis of the longer leg, 2^a, and for closing the lock it is only necessary to align the shorter leg, 2^c, with the opening in the case, and press the shackle inwardly. This movement bring the notches, 16, back into registration with the locking dogs, 17, which are immediately forced into said notches by their springs, 18. The inward movement of the shackle leg, 2^c, rotates the disk, 31, back to the initial position, carrying with it the pivoted ratchet, 36, and the final portion of such movement brings the tail 39, onto the cam surface, 40, fixed in the case, 1, for rocking the ratchet about its pivot so as to swing its tooth clear of the permutation disks, leaving them

free to be adjusted rotatably in either direction in the usual manner by means of the knob, 4. It may be understood that said disks are provided with lugs or bosses projecting from their mutually opposite surfaces to afford a driving connection from each disk to the next, by which they may be rotatively adjusted by turning the knob, 4, first in one direction and then in the other, until the deep notches of the disks are brought into registration with the pawl tooth, 30. The position of such a boss is indicated at 28^b on the disk, 28, shown in Figures 3, 5 and 6. The knob itself is interlocked with the outer disk, 28, by means of a pair of lugs, 4^a, engaging notches, 41, in a hub or collar, 42, associated with the disk, 28.

In the normal, completely closed position of the shackle, 2, as shown in Figure 3, the tooth, 30, of the spring-pressed pawl, 29, rests upon the periphery of the disk or plate, 31, adjacent its notch, 31^a, and preferably this disk is made of slightly larger diameter than the disks, 26, 27 and 28, of the permutation mechanism, so that while the plate, 31, remains in this position, supporting the tooth, 30, the permutation disks are free for rotative adjustment. However, since a slight outward pull on the shackle, 2, will register the notch, 31^a, with the tooth, 30, and permit the latter to drop onto the edges of the permutation disks, I prefer to form these edges with a series of "false" notches, 43, of relatively slight depth, but each of the same width as the deep notches, 26^a, 27^a and 28^a, which receive the pawl tooth, 30, when the lock is to be opened. Thus, in any attempt to "feel out" the combination by drawing out the shackle through this initial distance and manipulating the knob, 4, the movement of the knob and its connected tumbler or tumblers will be blocked or seriously hampered by engagement of the tooth, 30, with the false notches, 43, of the permutation disks. The slight movement of the parts permitted by engagement of the pawl tooth in one of the false notches will be substantially the same as that which might be experienced if the deep notch of one of the tumblers was registered with the pawl, thus making it impossible to distinguish between a false notch and the true effective notch in such manipulation of the lock. But all interference from the false notches is avoided in the normal and proper operation of the lock by leaving the shackle, 2, at the inner limit of its range, and thus leaving the plate, 31, in position to hold the pawl away from the notched edges of the permutation disks while they are being adjusted in accordance with the working combination of the lock. For steady- 50 ing the movement of the shackle and retaining it yieldingly in position in the casing, a bent spring arm, 44, of flat stock is anchored in the casing so that its angularly bent portion will engage in the groove, 2^b, of the shackle leg, 2^a, while an intermediate portion of the spring bears frictionally against the smooth surface of said leg.

While there is shown and described herein certain specific structure embodying the invention, it will be manifest to those skilled in the art that various modifications and re-arrangements of the parts may be made without departing from the spirit and the scope of the invention, and that the same is not limited to the particular form herein shown and described, except in so far as indicated by the appended claims.

I claim:

1. In a padlock including a case and a notched shackle slidable therein, a locking dog engage- 75

able with the notch of the shackle, the notch being wider than the portion of the dog which engages in it, thus permitting of an initial movement of the shackle toward unlocking position prior to withdrawal of the dog, permutation mechanism including a pawl and a plurality of notched tumbler disks rotatably adjustable for registering their notches with the pawl, and an additional notched disk coaxial with the others and normally blocking movement of the pawl but connected to be rotated by the said initial movement of the shackle through a distance sufficient to register its notch also with the pawl, permitting said pawl to enter the registered notches; and means by which such movement of the pawl shifts the dog to release the shackle.

2. In a padlock including a case and a notched shackle slideable therein, a locking dog engageable with the notch of the shackle, permutation mechanism including a pawl and a plurality of notched tumbler disks rotatably adjustable for registering their notches with the pawl, means for moving the pawl into said notches, said movement serving to withdraw the locking dog from the shackle, and a member co-axial with said disks and connected to be rotated by the shackle in its withdrawal from locked position, said member carrying a ratchet engageable with the peripheries of the disk for upsetting their registered arrangement as the lock is opened.

3. In the combination defined in claim 2, said member being permanently engaged with the shackle, whereby it is returned when the shackle is returned to locked position.

4. In the combination defined in claim 2, a cam surface provided in the casing positioned to act against a portion of said ratchet for holding it out of engagement with the peripheries of the disks when the shackle is in locked position but formed to release said ratchet for such engagement as the carrying member is rotated by withdrawal of the shackle.

5. In a padlock including a case and a notched shackle slideable therein, a locking dog engageable with the notch of the shackle, the notch being wider than the portion of the dog which engages in it, thus permitting of an initial movement of the shackle toward unlocking position prior to withdrawal of the dog, permutation mechanism including a pawl and a plurality of notched tumbler disks rotatably adjustable for registering their notches with said pawl, an additional notched disk co-axial with the others and normally blocking movement of the pawl but connected to be rotated by said initial movement of the shackle through a distance sufficient to register its notch also with the pawl, spring means arranged to shift the pawl into said registered notches, and an arm actuated by such movement of the pawl engaging the dog and shifting it for releasing the shackle.

6. In a padlock including a case and a notched shackle slideable therein, a locking dog engageable with the notch of the shackle, the notch being wider than the portion of the dog which engages in it, thus permitting of an initial movement of the shackle toward unlocking position prior to withdrawal of the dog, permutation mechanism including a pawl and a plurality of notched tumbler disks rotatably adjustable for registering their notches with the pawl, and an additional notched disk arranged coaxially with the others and normally blocking movement of the pawl but connected to be rotated by the said initial movement of the shackle through a dis-

tance sufficient to register its notch also with the pawl, permitting said pawl to enter the registered notches; and means by which such movement of the pawl shifts the dog to release the shackle, together with a ratchet carried by said additional disk and engageable with the peripheries of the tumbler disks for rotating them to destroy the registered arrangement of their notches during the opening movement of the shackle.

7. In a padlock including a case and a notched shackle slideable therein and having an externally exposed part, a locking member in the case engageable with the notch of the shackle, permutation mechanism including a plurality of notched tumblers rotatably adjustable and an externally exposed knob for adjusting them with their notches in registration and a member which enters said registered notches in the process of unlocking the shackle, the release of the shackle from the case requiring one of said external parts to be moved manually after such adjustment of the tumblers is effected, means within the case arranged to transmit said manually effected movement to at least one of the tumblers to rotate the same, and means for disengaging the aforesaid member from the tumbler notches during such rotation of the tumblers.

8. In a padlock including a case and a shackle slideable therein, both legs of said shackle being notched, movable locking means in the case engageable with both shackle notches and inter-connected for simultaneous movement into and out of such engagement, spring means urging the locking means toward shackle-engaging position, one leg of the shackle having a portion of substantial length extending within the casing beyond its notch and registerable with the locking means when the other leg of the shackle has been withdrawn from the casing in unlocked position, whereby the locking means is blocked against return to locking position until the shackle notches are again registered therewith, and mechanism in the casing for controlling release of the locking means.

9. In a padlock including a case and a shackle slideable therein, both legs of said shackle being notched, separate locking dogs in the case engageable with the shackle notches respectively, means by which said dogs are inter-connected for simultaneous movement into and out of such engagement, spring means urging said dogs toward shackle-engaging position, one leg of the shackle having a portion of substantial length extending within the casing beyond its notch registerable with the locking dog when the shackle is withdrawn in unlocked position, and thus serving to retain the dogs in released position until the shackle notches are again registered therewith, a permutation mechanism in the case having a part arranged to engage one of said dogs for moving it in direction to release the shackle, said permutation mechanism including a pawl and a plurality of notched tumbler disks rotatably adjustable for registering their notches with the pawl, means for moving the pawl into said notches when registered, said movement serving to withdraw the locking dogs from the shackle notches, and a member mounted co-axially with said disks and connected to be rotated by the shackle in its withdrawal from locked position, said member carrying a ratchet engageable with the peripheries of the disks for upsetting their registered arrangement as the lock is opened, said upsetting movement forcing the pawl out of the notches of the disks, whereupon the aforesaid

leg of the shackle serves to hold the dogs out of locking position.

10. In a padlock including a case and a shackle slideable therein, both legs of said shackle being notched, separate locking dogs in the case engageable with the shackle notches respectively, means by which said dogs are inter-connected for simultaneous movement into and out of such engagement, spring means urging said dogs toward shackle-engaging position, one leg of the shackle having a portion of substantial length extending within the casing beyond its notch registrable with the locking dog when the shackle is withdrawn in unlocked position, and thus serving to retain the dogs in released position until the shackle notches are again registered therewith, a permutation mechanism in the case having a part arranged to engage one of said dogs for moving it in direction to release the shackle, said permutation mechanism including a pawl and a plurality of notched tumbler disks rotatably adjustable for registering their notches with the pawl, and an additional notched disk arranged co-axially with the others and normally blocking movement of the pawl but connected to be rotated by the said initial movement of the shackle through a distance sufficient to register its notch also with the pawl, permitting said pawl to enter the registered notches; and means by which such movement of the pawl shifts the dog to release the shackle, together with a ratchet carried by said additional disk and engageable with the peripheries of the tumbler disks for rotating them to destroy the registered arrangement of their notches during the opening movement of the shackle.

11. In a padlock including a case and a notched shackle slideable therein, a locking dog engageable with the notch of the shackle, the notch being wider than the portion of the dog which engages in it, thus permitting of an initial movement of the shackle toward unlocking position prior to withdrawal of the dog, permutation mechanism including a spring-pressed pawl and a plurality of notched tumbler disks rotatably adjustable for registering their notches with the pawl to receive the latter under stress of its spring, means normally blocking such movement of the pawl but adjustable by the aforesaid initial movement of the shackle to permit said pawl movement, the tumbler disks having their peripheries formed with false notches to be en-

gaged by the pawl if the blocking member is moved to clear the pawl before the disks are properly registered.

12. In the combination defined in claim 11, said blocking means being formed as a disk mounted co-axially with the tumblers and having a substantially smooth periphery slightly larger in diameter than said tumblers which prevents engagement of the pawl in the false notches until said disk is shifted by said initial movement of the shackle.

13. In a padlock including a case and an externally projecting notched shackle slideable therein, a locking member in the case engageable with the notch of the shackle, permutation mechanism including a plurality of notched tumbler disks rotatably adjustable, and an externally projecting knob for adjusting them with their notches in registration as a part of the process of unlocking the shackle, one of said externally projecting parts being adapted to be moved manually in the process of opening the lock after such adjustment of the tumblers is effected, and a member engageable with at least one of the tumblers and movable rotatively about their common axis by said manual movement of said part for destroying the registered arrangement of the tumblers.

14. A padlock comprising a case having openings, a shackle having legs slideable in said openings, one of said legs being longer than the other, a shackle locking means in said case including a rotatable tumbler movable to release said shackle and means actuated by the long leg of said shackle in the unlocking movement of the shackle to turn said tumbler out of shackle releasing position.

15. A padlock comprising a case having openings, a shackle having legs slideable in said openings, one of said legs being longer than the other, shackle-locking means in said case engageable with the shorter leg, adjusting means including a movable indicator and a co-operating fixed index extending externally of the case, said adjusting means being operatively related to the shackle-locking means for adjusting it to a position at which the shackle is released, and means actuated by the longer leg of the shackle in the unlocking movement of the shackle to shift the adjusting means and its indicator out of its adjustment at shackle-releasing position.

DILLWYN M. BELL.
